DESIGN FOR A TEXTILE FABRIC

Frank C. Green, Flushing, N. Y., assignor to Dazian's, Inc., New York, N. Y.

Application July 30, 1937, Serial No. 70,741

Term of patent 3½ years

To all whom it may concern:

Be it known that I, Frank C. Green, a citizen of the United States, residing in Flushing, in the county of Queens and State of New York, have invented a new, original, and ornamental Design for a Textile Fabric, of which the following is a specification, reference being had to the accompanying drawing, forming part thereof, wherein—

The figure is a plan view of a textile fabric showing my new design.

I claim:

The ornamental design for a textile fabric substantially as shown.

FRANK C. GREEN.
